UNITED STATES PATENT OFFICE.

FRANK FUREDY, OF NEW YORK, N. Y.

ADJUSTABLE WRITING IMPLEMENT.

Application filed February 25, 1924. Serial No. 694,990.

To all whom it may concern:

Be it known that I, FRANK FUREDY, a citizen of the United States, and resident of New York city, in the county of New York and State of New York, have invented certain new and useful Improvements in Adjustable Writing Implements, of which the following is a specification.

My invention relates to writing implements of the class in which the marking element, such as a "lead," is adjustable, usually by longitudinal movement in the case or holder. The invention is broadly described as a writing implement to include the possibility that a pen point or stylus point may be employed in some cases instead of a lead or crayon; but usually the writing elements or points in an implement of this class are of some grade of pencil "lead" or crayon, and the invention structure will therefore be hereafter referred to as relating to pencils.

The general object of the invention is to provide in a pencil of this class, two leads or crayons of different qualities, usually of different colors, with improved means by which either may be easily and quickly projected to writing position while the other is retracted and concealed within the case.

A more particular object is to accomplish this result by a very simple, strong and durable mechanism, and further to preferably so arrange the parts that one of the leads may be withdrawn and the other projected by moving, usually rotating, a controlling element such as a cap or knob in one direction, and the last named lead may be retracted and the first one projected by movement or rotation of the controlling element in the opposite direction, without the necessity for any particular care or attention of the user, since the desired lead can be selected, or the leads interchanged, almost instantly by moderate movement of the controlling element.

A further object is to preferably so construct the mechanism that the same controlling element not only interchanges the leads but adjusts either of them when in working position, so that more or less of the lead protrudes beyond the case or the "point" thereof.

A still further object is to provide means by which a lead or either of them may not

only be projected, but it may be positively withdrawn by manipulation of the same controlling element, and without the necessity for pushing the lead back in as a distinct operation from manipulation of the controlling element which effects projection of the lead.

Another object is to provide an eraser in a conveniently accessible position, in connection with other features of the invention.

A still further object is to provide for the convenient mounting or location of an eraser in a pencil of this class and in connection with other features of the invention, as referred to above and hereinafter.

While structures embodying the invention and attaining the above stated and other advantageous results may vary considerably, I have selected as a representative embodiment of the invention, a single structure in which provision is made for the manipulation of two active leads in the general manner above referred to. The invention in its broader aspect is, however, not limited to the employment of two active leads. Some of the principles or structural features of the invention are also evidently applicable with advantage to a single active lead, and in fact, the structure as shown is fully operative when only one lead is inserted in a lead-holder or grip; and evidently therefore, the mechanism for the other active lead can in some cases be dispensed with.

The characteristics and advantages of the invention are further sufficiently explained in connection with the following detail description of the accompanying drawings, which show one exemplifying embodiment of the invention. After considering this embodiment, persons skilled in the art will understand that many variations may be made within the principles of the invention, and I contemplate the employment of any structures that are properly within the scope of the appended claims.

Figure 1 is a longitudinal section of a pencil embodying the invention in one form.

Figure 2 is a transverse section at 2-2, Fig. 1.

Figure 3 is an end view of a guiding and controlling member, which may be identified by these names, or as a "body" located or inserted in the main tubular structure or case.

Figure 4 is a side elevation of the same with a part broken away to save space in the drawing.

Figure 5 is a transverse section at 5-5, Fig. 1.

Figure 6 is a perspective view of the rotatable gear and gear carrier or inner cap with a part broken away.

The parts are contained or supported in 10 a tube 10 conveniently identified as a case or casing. In the upper portion of this is a fixed member 11, which may be identified as a controlling or guiding member, and which might be integral with the case, but 15 for manufacturing convenience and economy is almost necessarily made separate, and as shown is in the general form of a cylinder which has a close sliding fit in the case, so that when pressed into position, 20 usually with its upper end flush with the upper end of the case, it stays in place and there is usually no necessity for providing a stop such as a shoulder within the case to limit the inward movement of the guide member, although such a shoulder may be 25 provided if desired, at about the point 12. Any suitable means may also be provided for preventing upward displacement of the guide member, although such means is 30 usually superfluous.

The guide member is so dimensioned as to leave the lower interior part of the case entirely unobstructed, forming a tubular chamber 14 which provides ample room for 35 the lead holders or grips and the active leads. Desirably, the lower end of the casing consists in a detachable or "screw" tip 15 of tapered form, this detachable tip permitting ready access to the lead grips (referred to hereafter) and facilitating in some 40 cases the changing or replacement of the leads without any further detachment of parts, although in some cases the leads may be removed and replaced without detachment of the tip 15. In the point of the tip 45 is a cylindrical bore 16 of substantial length, dimensioned to fit leads of a usual or desired size with fair closeness, although the pencil structure is such that leads considerably 50 smaller than the point-bore can be used, if desired.

At diametrically opposite points the guide member 11 is bored longitudinally to provide two guide sleeves or tubular formations 18 and 19. In an inward surface of each of the sleeves is a guide or cam channel, identified as 20 for sleeve 18, and 21 for sleeve 19. Each of these guide channels includes a straight upper portion 23, 55 which is usually parallel to the main axis of the pencil, and a similarly straight longitudinal portion 24. The upper portion is usually shorter than the lower portion, and the two portions are joined by an oblique 60 or angular portion 25, the walls of the chan-

nel being suitably curved to afford a smooth movement of the controlled element in passing from the straight portions to and through the angular or cam portion of the channel.

To provide for the convenient carrying of 70 spare leads, cylindrical holes 30 are bored longitudinally in the guiding member down to a point near its lower end.

In each of the sleeves 18 and 19 a cylindrical actuating member is inserted, identified as 35 for cylinder 18, and 36 for cylinder 19. These actuating members may be conveniently identified by that name or in some cases, and especially in the claims, as 80 "impellers." Each of these impellers has a central longitudinal bore 37, and in each is formed a cam or screw track or slot, 38 for member 35, and 39 for member 36. Each slot extends through the tubular impeller from its outer wall to the central bore. Each of the cam tracks has two portions of 85 different slant or pitch, so that considering the cam track or slot as a screw, each includes an upper portion 40 of moderate 90 pitch, and a lower portion 41 of much steeper pitch, these portions of the cam slots preferably corresponding approximately in location and length to portions 20 and 24 of the guide channels in guide member 11. 95 The cam slots are of opposite pitch or lead or, in other words, one corresponds to a right hand and the other to a left hand screw thread. At the upper end of each impeller or screw 35 and 36, is a small pinion 100 45, nonrotatively secured to the controlling member in any suitable way, as by a stem or rivet 46 formed on the upper end of the impeller; or, of course, a screw could be employed instead of the rivet, fitted within the upper end of the bore of the impeller and clamping the pinion tightly thereon. The pinions are of sufficient diameter so that they overlap slightly the respective sleeves 18 and 19 and prevent downward displacement of the impellers 35 and 36, and upward displacement is prevented by a cap member referred to hereafter, or in any other convenient or suitable way.

A ring 50 is located against the upper end 115 of case 10 and in this ring is provided or located an internal gear 51 engaging the outward teeth of the pinions 45. The ring 50 and the gear are rotatively located and secured by a cap or sleeve member 52, which 120 may have a continuous or unapertured top portion or may merely have a shallow marginal flange extending inward to about the point 54 to overlie the upper margin of the ring. The cap is desirably also pressed or otherwise formed upon or about the ring so as to provide a shoulder at 56 underlying a lower margin of the ring, which is thus definitely held or located in respect to the cap. The cap or ring holder also has a cylindrical 125 130

- portion 57 mounted with a bearing fit on the upper end of the case 10. Moderately below the upper end of the case is formed a shallow annular channel 58. The lower end of the cylindrical cap portion 57 is bent or pressed inward, forming an annular rib 59 engaging in the groove 58 to prevent inadvertent outward displacement of the cap; and to provide for convenient application and removal of the cap in assembling the device, or if it is necessary to disassemble it, the cylindrical portion 57 is desirably slotted longitudinally to divide it into resilient portions or fingers 60 which yield outward when the cap is put in position and will then cause the shallow flange member 59 to snap into the channel 58, and thereupon the cap is rotatively secured and prevented from unintentional displacement.
- Desirably, a central portion of the cap end is cut out or left open to allow inspection of the pinions and to facilitate the proper positioning of the gear 51 in engagement with the pinions when the device is assembled or when cap 53 is replaced after removal for any reason. This aperture also permits discharge of the spare leads from their pockets 30 without removal of cap 53 or the gear. An additional or outer cap 70 is desirably also provided, which goes over a portion of cap 53 with a close fit and closes the aperture in cap 53 and provides for the rotation of the cap and gear 51. When it is desired to use a spare lead, access may be had to it by removing the outer cap 70; and loss of this cap will not affect the proper operation of the pencil.
- Provision is also made for mounting an eraser in a position where it is conveniently available. For this purpose the gear carrier or sleeve 52 is provided with a tubular extension 80 and a rubber eraser 81 is tightly but removably inserted in this extension. Outer cap 70 is proportioned to enclose the eraser and is usually also provided with a knurled portion 71 for the convenient rotation of the inner cap or gear carrier 52. The outer cap has a fit on extension 80 tight enough to insure the rotation of the gear carrier when the outer cap is turned, but at the same time the outer cap is removable by endwise movement to give access to the eraser. The spare leads may be removed by first removing the eraser. In some cases the eraser may be omitted and then either the inner or outer cap may have a closed end portion fitting down close to the pinions 45 to properly enclose them and to prevent accidental discharge of the spare leads.
- The active leads 75 and 76 are demountably secured in suitable grips or clutches 77 and 78, formed on or secured to the lower ends of stems 79 and 80. The clutches or grips may be simply in the form of short tubes of sheet metal provided at their lower ends with one or more slots 81, forming resilient fingers or grips which grasp the upper end of the lead when it is pushed into the tube. Other forms of grips or clutches may be provided if necessary or desirable.
- Each of the stems 79 and 80 includes a long straight upper portion 82 and a relatively short lower portion 83, these portions being slightly offset and connected by a short crank portion 84. At the upper end each stem has a short portion 85 extending through the corresponding cam slot 38 or 39 and into the corresponding guide groove or channel 20 or 21, as best indicated in Fig. 2. This stem portion 85 acts as an operating element or cam follower, and provides for the longitudinal and also the angular movement of the stem, as further explained below.
- The active leads 75 and 76 may in some cases be of identical character and color, and in that case a spare lead is provided in active position and always ready for practically instantaneous use when the other lead is worn out. But preferably the leads are of different characteristics; for instance, they may be of different degrees of hardness, or more especially they may be of different colors, since one important advantage of the invention is to provide different colored leads or crayons available for almost instantaneous interchange at the will of the user.
- The structure being assembled as shown in Fig. 1, the lead 76 which is shown in projected position, may be adjusted to make the exposed point of the lead longer or shorter, by rotating cap 53 or the outer cap 70 when that is provided. Angular member 85 of the corresponding stem 80 is at approximately the mid-length of the steep-pitch cam slot portion 41 and its end is in the lower straight portion 24 of the corresponding guide channel 20. This longitudinally central location of the member 85 with respect to the cam slot and guide channel portions corresponds to a relatively long piece of lead 76. The length of the cam and guide slot portions is sufficient to provide for a considerable range of adjustment, which is necessary as the lead wears away or is broken in use. During these adjustment movements of cap 53, the controlling cylinder 36 is rotating by the action of gear 51 upon its pinion 45, and the cam or screw slot 41 acts on stem member 85 to move it longitudinally, any rotation of the stem being prevented by engagement of the end of the member 85 in the straight guide channel portion 24. The rotation of the controlling member is therefore effective to move stem 80 longitudinally without rotation.
- Under the condition described, stem member 85 of the other stem 82 is in the upper, moderate-pitch portion 40 of the cam or

screw slot 38 of the other controlling member 35, and its end is in the upper straight portion 20 of guide channel 23. Therefore, while the rotation of gear 51 also causes rotation of controlling member 35 and longitudinal movement of stem 82, this movement is of restricted amplitude and not sufficient to cause any interference between the stems or leads during adjustment of the lead 10 which is in projected position.

If it is desired to interchange the leads, cap 53 or the outer cap 70 is simply rotated in an appropriate direction, which is the direction of movement for the inward adjustment of the projected lead, and this cap rotation is continued until the projected lead is entirely withdrawn and the other lead, 75 in this instance, is projected to active position and it may then be properly adjusted 20 for length, either inward or outward, by proper slight rotation of the cap. In the described continuous rotation of the cap to effect lead interchange, member 85 of stem 80 is pulled up without rotation of the stem 25 until it approaches angular portion 25 of the corresponding guide channel, this longitudinal movement of the stem being quite rapid, due to the steepness of pitch of the cam slot. At the same time, member 85 of stem 79 is moved downward without stem rotation at relatively slow speed, due to the moderate pitch 40 of the corresponding cam slot 20. The lead grips 77 and 78 are then 30 practically opposite, and the point of lead 35 76 is withdrawn within the chamber 14.

Continued rotation of the cap then causes both of the members 85 to pass in opposite directions through the diagonal guide channel portions 25; and in this movement the stems 79 and 80 are rotated a small fraction of a turn by the combined effect upon the members 85 of the cam slots and the angular guide channel portions. This slight simultaneous rotative movement of the stems 45 is effective through the cranked portions 83 so that the leads will properly clear each other in further movement, and especially so that lead 75, which has previously been 50 out of line with point-bore 16, is brought approximately or exactly in line with it, while lead 76 is carried out of line with the bore, and to a point near one side of the chamber 14, where it is out of the way of the other lead, which is now to be moved to 55 active or projected position.

Further rotation of the cap in the same direction causes lead 76 to be rapidly moved down into the tip bore and projected for use, and it then may be adjusted in a manner sufficiently obvious from preceding explanation. Meantime lead 76 has been withdrawn to approximately the position that lead 75 occupies in Fig. 1, although, of course, toward the opposite side of chamber 14. In 60 65 the movement of either lead to projected

position, while, as above stated, it has been brought approximately in line with the tip bore prior to entering the bore, it may, nevertheless, be slightly out of line; but in that case it is guided into the bore by the 70 tapered inner surface of the detachable tip 15.

To replace or change leads it is only necessary to bring one of the lead grips to approximately its lowermost position by rotation of the cap, whereupon the grip is exactly or almost exactly centered in relation to the tip bore 16, and the old lead may be removed and a new one inserted through the tip bore. When the parts are properly proportioned the lead grip may be exactly centered by contact with the inner walls of the tip 15 adjacent to the bore, or if the grip is not actually in contact with the tip walls it is in any event brought to approximately 80 centered position by the endwise movement and rotation of the stem, sufficiently described above. If any difficulty is encountered in inserting a new lead in this manner, the tip may be unscrewed, giving free access to chamber 14 and the lead grips, and especially the grip which is in the most extended position, with ample room for insertion of the lead. The mechanism may be manipulated for projection or retraction of the grips whether the tip is in position or not, or the lead may be inserted or removed when either grip 78 is positioned near the end of the tip 15, without removing the tip. 90 95

There is thus provided in simple and durable form a mechanism which permits either of two leads to be quickly placed in active position and adjustable for length, and which, of course, also permits both of them to be withdrawn to safe and convenient position within the pencil body when the pencil is not in use. Other operative or manipulative advantages of the invention will be readily understood by skilled persons without further explanation. 100 105 110

I claim:

1. A pencil comprising a case, a plurality of lead carriers supported for longitudinal and rotative movement therein, each lead carrier having a cranked lower portion, and means for simultaneously moving two of the lead carriers longitudinally in opposite directions and rotating them at certain points of their longitudinal travel. 115 120

2. A pencil comprising a casing having a tip provided with a lead bore substantially at the case axis, a plurality of lead carriers supported for longitudinal and rotative movement in the case, each carrier having an offset lower portion arranged to bring a lead carried by it substantially in line with the lead bore when the carrier is turned to one of its positions, and means for simultaneously moving two of the lead carriers longitudinally in opposite direc- 125 130

tions and rotating them at certain points of their travel, whereby the lead carried by either carrier may be projected in the axial line of the case for use or withdrawn to inactive position adjacent the case wall while the other lead is moved and positioned oppositely to the one just mentioned.

3. A pencil comprising a substantially cylindrical case having a tip provided with a lead aperture at the case axis, a plurality of lead supporting stems guided for longitudinal and pivotal movement within the case, each stem having an offset lower end portion and a lead grip thereon, means for partly rotating each stem at a certain point in its longitudinal travel, rotary stem impelling means co-operating with the stems to simultaneously move them longitudinally in opposite directions, and a revoluble operating member in exposed position and connected to said impelling means.

4. A pencil comprising a substantially cylindrical case having a tip provided with a lead aperture at the case axis, two lead supporting stems guided for longitudinal and pivotal movement within the case, each stem having a cranked lower end portion and a lead grip thereon, relatively fixed means in the case for partly rotating each stem at a certain point in its longitudinal travel, rotary stem impelling means having helical channels co-operating with the stem to simultaneously move them longitudinally in opposite directions, and an operating member revolubly mounted and accessible for manipulation and connected to said impelling means.

5. A pencil comprising a substantially cylindrical case having a tip provided with a lead bore at the case axis, a plurality of lead supporting stems within the case, each stem having a cranked lower portion and a lead grip thereon, a substantially cylindrical impeller for each stem rotatively mounted in the case, the impeller having a helical channel and the stem having a follower engaging the channel whereby the stem is moved longitudinally when the impeller is rotated, means cooperating with the stems to partly rotate them at predetermined points in their longitudinal travel, a revoluble operating element accessible exteriorly to the case, and means intermediate the operating element and at least two of said impellers by which, when the operating element is rotated the impellers are simultaneously rotated and the corresponding lead stems are simultaneously moved longitudinally in opposite directions.

6. A pencil comprising a substantially cylindrical case having a tip provided with a lead bore at the case axis, a plurality of lead supporting stems within the case, each stem having a cranked lower portion and a lead grip thereon, a substantially cylind-

rical impeller for each stem rotatively mounted in the case, the impeller having a helical channel and the stem having a follower engaging the channel whereby the stem is moved longitudinally when the impeller is rotated, relatively fixed means co-operating with the stems to partly rotate them at predetermined points in the longitudinal travel, a revoluble operating element accessible for manipulation exteriorly of the case, and gearing intermediate the operating element and at least two of said impellers by which, when the operating element is rotated the impellers are simultaneously rotated and the corresponding lead stems are simultaneously moved longitudinally in opposite directions.

7. A pencil comprising a substantially cylindrical case having a tip provided with a lead bore at the case axis, two impellers rotatively mounted in the case and each having a helical channel, lead supporting stems corresponding to the impellers and having portions extending therethrough, each stem also having a follower engaging in the corresponding impeller channel, relatively fixed means co-operating with the stems for guiding and partly rotating them at predetermined points of their longitudinal movement, an operating member revolubly mounted on the case and exposed for convenient manipulation, a gear connected to said operating member, and a pinion on each of the impellers engaging the gear, whereby, when the operating member is rotated, the impellers are simultaneously rotated, and one lead stem is moved lengthwise and angularly to project the lead carried by it through the lead bore, while the other stem is retracted and its lead is moved to inactive position near the case wall, reverse movement of the operating member serving to operate the lead stems and leads in reverse fashion.

8. A pencil comprising a substantially cylindrical case having a tip provided with a lead bore at the case axis, two impellers rotatively mounted in the case and each having a helical channel, lead supporting stems corresponding to the impellers and having portions extending therethrough, each stem also having a follower engaging in the corresponding impeller channel, relatively fixed longitudinal guide channels having diagonal portions and co-operating with the stems for guiding and partly rotating them at predetermined points of their longitudinal movement, an operating member revolubly mounted on the case, and exposed for convenient manipulation, a gear connected to said operating member, and a pinion on each of the impellers engaging the gear, whereby, when the operating member is rotated, the impellers are simultaneously rotated, and one lead stem is moved length-

- wise and angularly to project the lead carried by it through the lead bore, while the other stem is retracted and its lead is moved to inactive position near the case wall, reverse movement of the operating member serving to operate the lead stems and leads in reverse fashion.
9. A pencil comprising a case, a lead carrier supported for longitudinal and rotative movement therein, said carrier having a cranked lower portion and a lead grip thereon, a substantially cylindrical impeller mounted for rotation in the case and having a helical channel, the lead carrier having a member engaging said channel whereby the carrier is moved longitudinally upon rotation of the impeller, a relatively fixed guide channel in the case co-operating with the lead carrier to prevent rotation thereof during parts of its longitudinal travel and to move the carrier rotatively at a certain point, and a revoluble operating member in externally accessible position on the case and connected with the impeller to rotate the same.
10. A pencil comprising a case, a lead carrier stem having a cranked lower portion and a lead grip thereon, a substantially cylindrical impeller mounted for rotation in the case and having a helical channel, the lead stem passing through the impeller and having a member engaging said channel whereby the stem is moved longitudinally upon rotation of the impeller, and a relatively fixed guide channel in the case co-operating with the lead stem to prevent rotation thereof during parts of its longitudinal travel and to rotate the stem at an intermediate point in its longitudinal travel.
11. A writing implement comprising a casing including a chamber, a plurality of lead holders in the chamber, each adapted to support a lead in condition for active use, a rotary impeller for each lead holder, cooperative means provided in said impeller and a relatively fixed element in the casing to advance or retract the corresponding lead upon rotative movement of the impeller, said impellers being provided near one end of the casing with pinions, and a gear rotatively mounted on the casing and engaging the pinions for moving the impellers simultaneously.
12. A writing implement comprising a casing including a chamber, a revoluble operating member, two lead holders in the chamber each adapted to support a lead in condition for active use, a rotary impeller for each lead holder, cooperative means in said impeller and a relatively fixed element in the casing to move the lead holders simultaneously in opposite longitudinal directions upon rotative movement of said impellers, and means for partly rotating each lead holder at an intermediate point of its longitudinal travel.
13. An adjustable pencil comprising a casing, two parallel impellers therein, a guide member providing means for the revoluble mounting of the impellers, each impeller and an adjacent part of the guide member being provided with co-operative channels, a stem for each impeller having a portion engaging the impeller channel and the corresponding channel in the guide member, the stems being arranged for longitudinal to-and-fro movement in parallel relation within the impellers, a lead grip on the lower end of each stem, and means for rotating the impellers simultaneously.
14. An adjustable pencil comprising a casing, two revoluble impellers therein, a guide member providing means for the revoluble mounting of the impellers, each impeller and an adjacent part of the guide member being provided with co-operating channels, a stem for each impeller having a portion engaging the channel in said impeller and the corresponding channel in the guide member, a lead grip on the lower end of each stem, a pinion secured on the upper end of each impeller, a gear engaging both of the pinions and rotatively mounted in relation to the casing, and a cap secured to move with the gear and having an exposed portion for manipulation.
15. An adjustable pencil comprising a casing, two revoluble impellers therein, a guide member providing means for the revoluble mounting of the impellers, each impeller and an adjacent part of the guide member being provided with co-operating channels, a stem corresponding to each impeller and having a portion engaging the impeller channel and the corresponding channel in the guide member, a lower portion of each stem being offset in relation to its upper portion, a lead grip on the lower end of each stem, and means for rotating the impellers simultaneously.
16. An adjustable pencil comprising a tubular casing, a guide member located in an upper portion thereof, the guide member being formed with two opposite cylindrical chambers, a cylindrical impeller revolvably mounted in each of the chambers and provided with a screw slot having portions of different pitches, the guide member being provided adjacent each impeller with a guide channel having offset upper and lower portions and an angular connecting portion, a stem having a portion movable longitudinally in a central bore of each impeller and also having a portion extending through the screw slot of the impeller and engaging in the adjacent guide channel, each stem having a cranked lower portion, a lead grip at the lower end of each cranked portion, and means including an exposed finger-grip portion for simultaneously rotating the impellers to project or retract

either of the leads with simultaneous opposite movement of the other, and to adjust the length of either lead when projected.

17. In a pencil or similar structure, a tubular casing, an actuating member mounted for rotation therein, said member having a screw slot, a relatively stationary guide channel having straight upper and lower portions and an angular connecting portion, and a stem provided with an offset lead grip and having a member co-operating with said screw slot and channel.

18. In a pencil or similar structure, a tubular casing, an actuating member mounted for rotation therein, said member having a screw slot, a relatively stationary guide channel having straight upper and lower portions and an angular connecting portion, and a stem provided with a lead holder and having a portion co-operating with said screw slot and guide channel and also having its lower portion offset.

19. In a pencil or similar structure, a tubular casing, a long cylindrical actuating member mounted for rotation therein, said

member having a screw slot, a relatively stationary guide channel having straight upper and lower portions and an angular connecting portion, and a lead holder arranged to support an active lead in the casing and also having a portion co-operating with said screw slot and guide channel upon rotation of the actuating member to move the lead holder longitudinally and at a certain point to move it angularly.

20. An adjustable pencil comprising a tubular casing, a plurality of lead holders therein, means for adjusting the lead holders longitudinally of the casing to project and retract the leads, a rotatable member at one end of the casing for operating said adjusting means, said rotatable member having a tubular extension, an eraser removably mounted in said extension and a removable outer cap engaging the rotatable member to rotate the same and also enclosing the eraser.

Signed at New York city, in the county of New York and State of New York, this 23rd day of February, A. D. 1924.

FRANK FUREDY.
